WATER-TIGHT RECEPTACLE FOR
BATHERSEmmett H. Moore, Aspinwall, and Florence C.
Eiser, Pittsburgh, Pa.

Application April 5, 1934, Serial No. 719,216

4 Claims. (Cl. 224—26)

This invention relates to improvements in the class of receptacles and pertains particularly to a water-proof receptacle designed for use by bathers for the carrying of cigarettes and matches or a cigarette lighter.

The primary object of the present invention is to provide a new and novel type of receptacle of the above described character, which may be conveniently attached to a belt of the bather's suit and in which novel means is employed for effecting the connection of the receptacle with the carrying means therefor.

Another object of the invention is to provide a receptacle of the above described character having a novel means dividing the receptacle into two compartments whereby cigarettes and means for lighting the same may be kept separate.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view in top plan of the receptacle embodying the present invention with the top or cover removed.

Figure 2 is a vertical sectional view through the receptacle, taken upon the line 2—2 of Figure 1 and with the top applied.

Figure 3 is an interior view of the top.

Referring to the drawing wherein like numerals of reference designate corresponding parts throughout the several views, the numeral 1 indicates the body of the present receptacle while the removable top therefor is indicated generally by the numeral 2. The body portion of the receptacle may be of cylindrical or oval cross section, as desired, the form here illustrated being cylindrical.

The bottom wall 3 of the body 2 is provided with the upstanding hollow projection 4 which extends up into the body of the receptacle and is open only at its lower end so that water cannot enter the receptacle through this hollow projection. The upper end of the body 1 is of reduced diameter forming the relatively tall mouth flange 5. This flange, being of an overall diameter less than the overall diameter of the body of the receptacle, forms therewith the outer shoulder 6 upon which rests a ring gasket 7. Above the

gasket 7, the outer face of the portions 5 of the receptacle is provided with one or more bayonet slots 8, the entrance ends of which open through the top edge of the portion of the body in which they are formed.

The cap 2 is designed to fit down over the annular mouth portion 5 of the receptacle and bear against the gasket 7, and formed upon the inner face of the circular wall portion of the cap are projections or lugs 9 corresponding in number with the bayonet slots 8 which enter the bayonet slots and secure the cap firmly in position against the gasket after it has been given a partial turn about the mouth portion 5.

The attachment of the receptacle 1 to the belt or another part of the clothing of the person carrying the receptacle, is effected through the medium of a resilient spring metal clip which is indicated as a whole by the numeral 10. This clip comprises the relatively long arm portion 11, the right angularly directed lower end portion 12, which extends from the arm, and an upturned portion 13 forming a continuation of the portion 12, which terminates in a laterally and downwardly directed spring lip 14. As shown, the arm 11 is longitudinally curved so as to form a portion intermediate its ends which is bowed outwardly away from the upstanding portion 13. Connection is made between the receptacle and the carrying clip 11 by inserting the portion 13 and the tongue 14 into the hollow projection 4, which forms an integral part of the bottom of the receptacle, so as to bend the spring lip 14 inwardly and bring the sharpened edge portion 15 in contact with the wall of the hollow projection 4 in which it is located. When this assembly of the parts is accomplished, the wall of the receptacle body 1 will contact with the upper and lower portions of the resilient arm 11, as illustrated, so that the upper free end of the resilient arm may be flexed away from the receptacle body to permit a belt or some other portion of the clothing to be inserted between the arm and the receptacle whereby the receptacle will become firmly attached to the clothing.

Within the receptacle is disposed in vertical position the tubular body 16, the lower end of which receives the projection 4. It will thus be seen that the projection 4 serves two functions, one of which is to provide a receiver for the parts 13—14 of the spring clip, while the other is to provide a means for securing the inner tubular receptacle within the outer or main receptacle. This inner tubular receptacle 16 provides a means for retaining in the main receptacle matches or a

lighter, while the portion of the main receptacle surrounding this tubular receptacle may be filled with cigarettes.

From the foregoing, it will be readily apparent that the device herein described provides a convenient means for a bather to carry with him cigarettes or other material which it is desired to keep dry, and also that a novel means is employed for securing the receptacle to the clothing of the user.

What is claimed is:—

1. In a device of the character described, a receptacle, a removable top for the receptacle, a hollow outwardly opening projection in the bottom of the receptacle, and a resilient carrying clip comprising a resilient arm adapted to position against the side of the receptacle and a resilient lip carried by the arm and adapted to frictionally engage in said hollow projection.
2. A device of the character described, comprising a receptacle having a bottom wall and an open top, a cover for said top, a projection extending upwardly into the receptacle from said bottom wall, said projection being hollow and opening downwardly through the bottom wall, and means for attaching the receptacle to the carrier, comprising a spring arm having a lateral projection at one end from which a vertical member extends which terminates in an outwardly and downwardly extending spring tongue, said spring tongue and vertical extension being insertible into the said hollow projection for frictionally coupling the receptacle with the resilient arm,

said resilient arm being held in firm contact against the outer wall of the receptacle.

3. A device of the character described, comprising a receptacle having a bottom wall and an open top, a cover for said top, a projection extending upwardly into the receptacle from said bottom wall, said projection being hollow and opening downwardly through the bottom wall, means for attaching the receptacle to the carrier, comprising a spring arm having a lateral projection at one end from which a vertical member extends which terminates in an outwardly and downwardly extending spring tongue, said spring tongue and vertical extension being insertible into the said hollow projection for frictionally coupling the receptacle with the resilient arm, said resilient arm being held in firm contact against the outer wall of the receptacle, and a cylindrical body within the receptacle disposed vertically and having said projection extending into its lower end, the cylindrical body forming a central compartment within the receptacle.

4. A receptacle of the character described, comprising a hollow body having one end open, a cap for closing said open end, a body extending vertically in the receptacle upon the wall opposite the open end, and a tubular body within the receptacle and having the said wall supported body frictionally engaged in one end thereof whereby the tubular body is held in position and forms a central chamber within the receptacle.
